UNITED STATES PATENT OFFICE

EARL E. BERRY, OF BELOIT, WISCONSIN, ASSIGNOR TO BELOIT IRON WORKS, OF BELOIT, WISCONSIN, A CORPORATION OF WISCONSIN

SELF-BALANCING STEAM FITTING

Application filed May 29, 1931. Serial No. 540,823.

This invention relates in general to pipe joints or couplings between rotating and non-rotating conduits for fluids or gases under pressure. It has more particular reference to steam fittings of the type adapted for drying cylinders of paper drying machines.

I have aimed primarily to provide an improved steam fitting which will be self-balancing in the sense that variations in steam pressure in the course of operations will not unseat the fitting in the case of increases in pressure or cause excessive friction on the sealing surfaces in the case of decreases, and that the steam pressure is utilized as an agent in acting on predetermined areas of the structure to maintain the balanced condition contemplated by my invention.

Another object of my invention is to provide a self-balanced steam fitting in the nature of a unit supported primarily by its necessary inlet or outlet pipes and having no extraneous supports or fixtures for taking endwise thrust of the steam. This is particularly desirable and advantageous in connection with paper drying machines when contrasted with the prior practice in this art.

Another object is the provision of an improved assembly of a steam fitting on a rotary drier journal characterized by the centering of the fitting on the journal in a novel manner permitting certain displacements of the fitting to compensate for misalignment caused during operation by expansion and contraction of the steam pipes.

Still another object is to provide a generally improved structure of the character described whereby the fitting may be displaced incidental to the varying conditions during operations without setting up undue stresses or causing the fitting to leak at the sealing joints.

Other objects and attendant advantages will be appreciated by those skilled in this art as the invention becomes better understood by reference to the following description when considered in connection with the accompanying drawings, in which—

Figure 1 is an end elevation showing the

application of my self-balancing steam joint to several cylinders of a paper drying machine;

Figure 2 is a side elevation of the structure shown in Fig. 1;

Fig. 3 is an enlarged vertical section through the steam fitting proper taken on the section line 3—3 of Fig. 1;

Fig. 4 is a plan view of the parts shown in Fig. 3;

Fig. 5 is a cross-section taken on the line 5—5 of Fig. 4;

Fig. 6 is a detailed section taken on the line 6—6 of Fig. 4; and

Fig. 7 is a section taken on the line 7—7 of Fig. 4, showing the fitting in side elevation.

In the drawings I have illustrated a typical application of my invention to several drying cylinders 8 of a paper drying machine. These cylinders, varying in size and sometimes weighing tons, are equipped at the ends with trunnions 9 journaled in suitable supporting bearings 11. In the instant case, these bearings are carried by a suitable supporting structure 12 in turn mounted on a base or frame structure 13 usually located at a floor level.

It is customary in this art to apply a steam fitting in the end of the drier journal here shown, for the purpose of supplying steam through the hollow journal to the interior of the cylinder and also for the purpose of removing the condensate. Because of the large size and length of the cylinders and the temperatures involving, there is an appreciable lengthwise expansion and contraction of the cylinders which is allowed at the steam fitting end by reason of the journal at the opposite end having end thrust against its supporting bearing. With my present invention this displacement is of no consequence because the steam fitting moves lengthwise with the journal and the steam pipes have a flexible or universal connection at their lower ends as will be presently disclosed.

Steam is supplied to the cylinders from a main header pipe 14 and individual supply pipes 15 connecting to the respective fittings, 160

and the condensate discharges from the fittings through pipes 16 which connect to the main outlet pipe 17. These pipes 15 and 16 connect to the pipes 14 and 17, respectively, 5 through suitable universal couplings 18 which allow play for expansion and contraction of the pipes 14 and 17. The valves shown in connection with this piping are purely incidental and the whole installation 10 is merely for purpose of illustration of the principles of my invention.

Referring now more particularly to Figs. 3 and 4, it will be seen that the steam and condensate pipes are fixed to a main fitting 15 designated generally by 18, having an interior compartment 19 with which the steam pipe communicates and another compartment 21 with which the condensate pipe communicates, these compartments being separated 20 one from the other. Another condensate pipe 22 extends from the compartment 21 through the steam compartment 19 and through the journal into the drying cylinder where suitable means is provided for collecting the condensate. Usually this pipe 22 or an extension thereof extends to the bottom of the cylinder where it has an inlet end and establishes a siphon for discharge of the condensate. A locating nut 20 serves to hold 25 the inlet end of the pipe 22 in proper position. This arrangement is not material to my present invention, since any suitable or preferred means may be employed for removing condensate from the cylinder. It is, 30 however, desirable from a practical standpoint, to embody the condensate discharge means with the steam fitting.

Steam from the compartment 19 of the main fitting discharges into the end of the 10 rotating journal and my present invention deals primarily with the problems involved in maintaining a steam tight joint between this main fitting and the journal under the varying conditions of operation. It has 15 been customary in the past to interpose a bearing ring between the main fitting and the end of the journal and to employ springs for keeping the joint steam tight. In such cases the rubbing surfaces forming the steam 20 joint are subject to considerable pressure in order to maintain a tight joint, thus causing these surfaces to wear away rapidly and creating considerable friction which is translated into power required to drive the paper 25 machine. It has also been known to provide a balanced effect as disclosed in Aldrich Patent No. 1,774,624, and a number of my prior patents of which No. 1,688,172, is an example, by means remote from the drying cylinder. 30 In providing a fixed resistance against which the thrust of the fitting is taken, the opposite thrust being taken against the journal bearing at the opposite end of the cylinder. This, however, involves the use of special supports or fixtures for the end thrust

of the fitting as well as special provision in the supporting bearings for the end thrust set up in the drier. The present invention while embodying some of the advantages of prior practice is, so far as I am aware, an 70 advance in this art particularly in that self-balancing effects and minimum wear of the rubbing surfaces of the joint are obtained in a unit assembly eliminating extraneous supports as well as objectionable end thrusts 75 on the cylinder and having facilities for maintaining the fitting in centered relation to the journal yet permitting displacement of the main fitting to compensate for the shear misalignment thereof incidental to the 80 expansion and contraction of the inlet and outlet pipes during operation.

In the present embodiment of my invention the main fitting 18 has at its steam discharge end a spherically shaped seat 23 which receives the similarly shaped face of a bearing ring 24 which may be of carbon impregnated with graphite as claimed in my Patent No. 1,769,905. The opposite face 25 of this ring is preferably a straight wall in a plane at right angles to the axis of rotation of the journal and bears against a similar surface of an annular flange 26 fixed to the journal. In this instance the flange 26 is integral with a collar 27 threaded onto a sleeve 28 in turn fixedly secured by bolts 29 to the journal 9 and constituting an extension thereof. The bearing surfaces 23 and 25 may have depressed areas 31 of the nature disclosed in 90 Patent No. 1,666,637, for the purpose of further promoting a steam tight joint. A second bearing ring 32 is seated on the collar 27 for radial bearing on the surface 33 thereof and bears against the inner straight wall surface 34 of the flange 26. A yoke structure to be presently described connects this bearing ring 32 with the outer end of the main fitting and ties the fitting assembly together, this yoke structure including at the inner end 100 a ring member 35 seating on the bearing ring 32. To the end of the main fitting remote from the journal is applied an expansible compartment 36, an end wall of which constitutes a part of the yoke structure referred to. This compartment is formed by a tubular, flexible, metallic sylphon 37, one end of which is attached to an end plate 38 integral with the main fitting, and the opposite end to an end plate 39. Steam is admitted to the compartment 36 through a passage 41 (Figs. 4 and 5) communicating with the compartment 19. Tie rods 42 and 43 which also serve as thrust rods, and form part of the yoke structure above referred to, 110 connect the end plate 39 to the ring member 35, at diametrically opposite sides of the latter. The tie rods are located at one end in annular and elongated holes 44 and 44' in the ears 45 and 45', respectively, on the ring 115 120 125 130

member 35, and at the opposite end in annular holes 46 and 46' in the ears 47 and 47', respectively, on the end plate 39. The holes 44' and 46' are tapered lengthwise and elongated in a vertical plane, as shown in Figs. 5 and 7, to allow for certain play of the tie rod 43 when the main fitting is displaced as will be presently noted. A coiled expansion spring 48 mounted on each tie rod intermediate 10 ate its supporting ear 47 and an ear 49 integral with the end plate 38 acts normally to urge the main fitting toward the rotary journal and to hold the bearing members in sealing contact. The hole 51 through which the tie rod 43 passes in the ear 49 is vertically elongated from end to end as shown in Figs. 6 and 7. An ear 52 projecting laterally from the main fitting 18 has an annular opening 53 through which the tie rod 42 passes. The 20 annular openings in the ears 45, 47, 49 and 53 through which the rod 42 passes are close-fitting so that the main fitting is held against horizontal displacement at right angles with respect to the pipes 15 and 16. It will be noted that by reason of the connection of the main fitting with the tie rods and the connection of the latter to the ring member 35 which in turn is centered on the journal through the intermediary of the bearing ring 32, the main fitting is normally centered with respect to the journal. While the yoke structure just described has additional functions which will be presently noted, it should be observed at this point, that this structure 30 allows a limited vertical displacement of the main fitting in order to compensate for vertical expansion and contraction of the pipes 15 and 16. This vertical movement of the main fitting is translated through the tie rod 43 to the ring member 35 causing the latter to rotate slightly on the journal and displacing the tie rod 43 to a slight angle relative to the center line of the journal, the ring member 35 moving in a clockwise direction 40 45 when the fitting is raised by expansion of the pipes and in a counter-clockwise direction when lowered by contraction. This freedom of motion is allowed by the elongated slots or openings 44' and 51', and the 50 flexibility of the sylphon 37 allows the end plate 39 to follow the alignment of the tie rod 43. In actual practice the maximum expansion and contraction of the supporting pipes 15 and 16 is approximately $\frac{1}{6}$ ", it being evident that this is a variable depending on sizes and temperatures.

Attention is now directed to the action of the steam which is supplied through the pipes 14 and 15 and the fittings to the interior of the cylinders 8 for the purpose of heating these cylinders. The sheet of paper is dried in the course of its travel over the rotating heated cylinders. As above-mentioned, my invention deals with the problems incidental 60 to supplying steam to the rotating cylinder

and to the varying conditions incidental to the changes in pressure and temperature. In order to secure the desired balance of the main fitting 18 the effective area of the expansible compartment 36 is, according to my invention, equal or slightly greater than the effective area of the compartment 19. The pressure of the steam against the end plate 39 of the expansible compartment is resisted through the yoke structure above described 70 which resistance is taken by thrust against the flange 26 of the journal. According to my invention, however, this pressure against the flange 26 is balanced by the action of steam pressure in the opposite direction in an annular channel-shaped chamber 54 in the face of the bearing ring 32 opposite the face 34, the steam being admitted to the chamber 54 through one or more passages 55 communicating with the interior of the main fitting. 75 The effective area of the chamber 54 is substantially equal to that of the compartment 19, so that the effective endwise pressures in compartments 19, 36 and 54, that is, parallel with the axis of the fitting are substantially 80 equal, thus making all forces of the steam in its action on the fitting substantially balanced. It is obvious, however, that with a strictly balanced condition no pressure would be applied to maintain the bearing surfaces 23, 25 and 34 in sealing contact, with the result that the fitting would leak steam. For the purpose of keeping these surfaces steam tight, in one phase of my invention I employ the 85 springs 48, the pressure of which acts with equal force on said surfaces 23, 25 and 34 and with only sufficient force to keep these surfaces or joints steam tight. In this way but minimum pressure is acquired on the bearing surfaces irrespective of variations in the 90 steam pressure and consequently the friction and wear are reduced to a minimum. My invention also contemplates maintaining the desired pressure on the surfaces 23, 25 and 34, without the use of the springs 48, the desired pressure being exerted by the steam in the compartment 36 by reason of the differential in effective areas between this compartment and the steam compartment 19, the effect 95 of which is to exert a force against the main fitting in addition to the balanced opposite forces against the end plate 39 and the flange 26, sufficient to keep the bearing joints steam tight.

It should be apparent from the foregoing that with my invention it is not necessary to employ supports or thrust resisting means extraneous to the cylinders, other than the support for the pipes 15 and 16; in other words, the fitting assembly is in the nature of a unit supported entirely by the cylinder journal and the one or more pipes such as 100 105 110 115 120 125 130 15 and 16, essential to the functioning of the device. It should also be noted that, in addition to the self-balancing features, the fitting

proper, that is, the parts attached to or directly assembled with the main casing 18, are normally centered with respect to the journal and are at all times maintained in 5 parallel relation with the journal by reason of the novel yoke structure. Another advantage is the facility afforded by reason of the flexibility of the sylphon 37 in the assembly with the yoke structure, for the shear mis-
10 alignment of the fitting casing 18 caused during operation by expansion and contraction of the pipes 15 and 16. It should be noted, however, that this misalignment occurs only in a vertical direction and that the fitting is
15 anchored by the ears 46, 49 and 52 to the tie rod 42 and oscillates about this rod at the same time the ring member 35 oscillates on its centered mounting on the journal. In this displacement, the bearing ring 24 moves in
20 the plane of its surface 25 upon and with respect to the opposite surface on the end of the journal. A further displacement occurs by reason of expansion and contraction of the pipes 14 and 17 in a horizontal plane, thus
25 causing the fitting assembly as a whole, to be oscillated about the axis of the journal.

While my invention is particularly adapted for application to the journal of a drying cylinder heated by steam, it may be applied 30 to other rotary conduits and to devices other than drying cylinders wherein the same functions are desired. It should be understood, therefore, that the term "steam" as used in the claims means any fluid or gas having the
35 properties of heat and pressure.

It should be apparent that in the practice of my invention changes may be made in the details of construction and in size and proportions without departing from the spirit 40 of the invention and the scope of the appended claims, in which—

I claim:

1. In combination, a hollow rotary journal, a supporting bearing for the journal, a main 45 steam fitting having steam supply and condensate outlet pipes connected thereto and serving to support it, a bearing ring interposed between and having bearing contact with said fitting and the end of said journal
50 and allowing motion of the fitting in a plane at right angles to the axis of the journal without breaking said bearing contact, and means operative between said fitting and the
55 journal for maintaining the fitting in a balanced condition and the bearing surfaces in sealing contact, said means including a ring rotative on the journal, an expansible compartment on the fitting, and tie-rods connecting said ring and a wall of said compartment responsive to the steam pressure therein, normally maintaining the fitting in centered relation with respect to the journal, said fitting having capacity for movement in said
60 plane with respect to said ring and said wall

to compensate for expansion and contraction of said pipes.

2. In combination, a hollow rotary journal, a supporting bearing for the journal, a main steam fitting having bearing contact against the end of the journal and supported by one or more pipes serving to conduct steam to or from the journal, an expansible compartment mounted on said fitting in axial alignment therewith and having a transverse wall responsive to the fluid pressure within the fitting, and means exterior of the fitting connecting said transverse wall with the journal so that the resistance of the fluid pressure against said wall is taken against the journal, a bearing ring on the journal through which said means connects to the journal, said bearing ring having an area acted on by the steam pressure in a direction opposed to that acting against said transverse wall whereby to maintain the fitting in substantial balance, said connecting means permitting displacement of the fitting with respect to the journal to compensate for expansion and contraction of said pipes without breaking the bearing contact between the fitting and the journal.

3. In combination, a hollow rotary journal, a supporting bearing for the journal, a main steam fitting having bearing contact against the end of the journal and supported by one or more pipes serving to conduct steam to or from the journal, an expansible compartment mounted on said fitting and communicating with the interior thereof, including a tubular sylphon fixed to one end of the fitting and having its opposite end free and responsive to the fluid pressure within the fitting, and means exterior of the fitting connecting said movable wall with the journal so that the resistance of the fluid pressure against said wall is taken against the journal, the parts being constructed so that the main fitting is in substantial balance between the journal and said movable wall and so that the fitting is adapted for displacement with respect to the journal to compensate for expansion and contraction of said pipes without breaking the bearing contact between the fitting and the journal.

4. In combination, a hollow rotary journal, a supporting bearing support for the journal, a steam fitting supported by steam inlet and condensate outlet pipes and having bearing contact against the end of the journal, means connecting the steam fitting to the journal and carrying the thrust of the steam pressure tending to unseat the fitting, a bearing ring on the journal through which said means connects to the journal, and a tubular sylphon compartment interposed between the fitting and said means subject to the steam pressure within the fitting, said bearing ring having an area subject to said steam pressure in a direction opposite to said thrust, the steam effective areas of said ring and said

5 sylphon compartment being such as to maintain the fitting in substantial balance, the arrangement of the fitting between the journal and said sylphon compartment serving to provide for displacement of the fitting with respect to the journal to compensate for expansion and contraction of said pipes without breaking the bearing contact with the journal.

10 5. A self-balancing steam joint of the character described including a main fitting supported by the steam and condensate pipes and having bearing contact against the end of a hollow rotating journal, and means connecting said fitting to the journal so that the thrust of the steam pressure tending to unseat the fitting is taken against the journal, including a tubular sylphon compartment mounted on the end of the main fitting, remote from the journal, a bearing ring mounted on the journal, and tie-rods between said sylphon compartment and said bearing ring, said fitting being pivotally connected to one of said tie-rods and adapted for vertical displacement with respect to the journal to compensate for expansion and contraction of said pipes without breaking the bearing contact between the fitting and the journal.

6. In combination, a hollow rotary journal, 30 a supporting bearing for the journal, a main steam fitting supported by steam and condensate pipes, and having bearing contact against the end of the journal permitting motion of the fitting with respect to the journal in a plane at right angles to the axis of the journal, an expansible compartment mounted on the main fitting, including a tubular sylphon attached at one end to the fitting and at its opposite end to a freely movable wall, said compartment being subject to the steam pressure within the compartment of the main fitting, a ring member mounted for rotative movement on the journal, and tie rods connected at one end to said ring member and at the opposite end to said movable wall serving to transmit to the journal the end thrust from the steam pressure in the fitting tending to unseat the fitting.

7. The combination set forth in claim 6, 50 including a bearing ring interposed between said ring member and the journal and having an annular channel-shaped compartment subject to the steam pressure in the compartment of the main fitting and arranged so that said pressure acts against the journal in a direction opposite to that of the aforementioned thrust, the steam effective areas of the compartment in the main fitting, the expansible compartment and the compartment in said ring member being substantially equal so as to effect a balanced condition of the main fitting.

8. The combination set forth in claim 6, 60 including a bearing ring interposed between said ring member and the journal and hav-

ing an annular channel-shaped compartment subject to the steam pressure in the compartment of the main fitting and arranged so that said pressure acts against the journal in a direction opposite to that of the afore-mentioned thrust, the steam effective areas of the compartment in the main fitting, the expansible compartment and the compartment in said ring member being substantially equal so as to effect a balanced condition of the main fitting, and tension exerting means acting between the afore-mentioned end wall and the main fitting tending to urge the latter toward the journal to keep the bearing joints in steam tight contact.

9. The combination set forth in claim 6, including a bearing ring interposed between said ring member and the journal and having an annular channel-shaped compartment subject to the steam pressure in the compartment of the main fitting and arranged so that said pressure acts against the journal in a direction opposite to that of the aforementioned thrust, the steam effective areas of the compartment in the main fitting, the expansible compartment and the compartment in said ring member being substantially equal so as to effect a balanced condition of the main fitting, but with the effective area of the expansible compartment slightly greater than said other compartments so that an additional steam force will be exerted against the main fitting tending to urge it toward the journal to keep the bearing joints in steam tight contact.

10. In combination, a hollow rotary journal, a supporting bearing for the journal, a steam fitting supported by a steam supply pipe and having bearing contact against the end of the journal, a bearing ring collared on the journal in position to take against the journal the end thrust of the steam pressure within said fitting tending to unseat the fitting, an expansible compartment mounted on the fitting subject to the steam pressure within the compartment of the fitting and having a movable transverse wall responsive to said steam pressure, means connecting said wall and said bearing ring for transmitting the endwise pressure thrust of the steam against the journal, said bearing ring having a surface subject to the pressure of the steam within the fitting and arranged so as to act against the journal in opposition to said thrust, the effective pressure areas of the compartment in said fitting, the expansible compartment and the bearing ring surface being substantially equal so that the main fitting will be in substantial balance, and means exerting a pressure against said fitting sufficient to maintain it in steam tight contact with the journal.

11. In combination, a hollow rotary journal, a supporting bearing for the journal, an annular flange on the journal having

an outer end face and an inner end face in parallel planes transverse to the axis of rotation, a steam fitting having a steam supply pipe and a condensate pipe, a bearing ring interposed between the steam fitting and the outer end face of said flange, and means for maintaining the steam fitting in operative relation with the journal including a bearing ring fitting against the inner face of said flange and having radial bearing on the journal, and a yoke structure attached to the steam fitting through the intermediary of a tubular sylphon and having a ring member seating against the second mentioned bearing ring to hold it against said flange, said yoke structure together with its ring member and sylphon serving to normally hold the fitting in centered relation to the journal and permitting displacement of the fitting in said transverse plane to compensate for expansion and contraction of said pipes.

12. In combination, a hollow rotary journal, a supporting bearing for the journal, a steam supply fitting, a bearing ring intermediate the steam fitting and the journal adapted to have sealing contact with said parts, the steam fitting including a tubular sylphon, and a yoke structure operating between the sylphon and the journal to normally maintain the fitting in centered relation to the journal, said sylphon serving to effect substantial balance of the steam pressure in respect to the fitting and bodily displacement of the steam fitting in a plane transverse to the axis of the journal in order to compensate for expansion and contraction of the steam fitting pipes.

13. In combination, a hollow rotary journal, a supporting bearing for the journal, a steam supply fitting, a bearing ring intermediate the steam fitting and the journal adapted to have sealing contact with said parts, a yoke structure connected at one end to the steam fitting having a centered bearing on the journal, the yoke structure serving to normally maintain the fitting in centered relation to the journal and permitting displacement of the steam fitting in a plane transverse to the axis of the journal to compensate for expansion and contraction of the steam pipes, and a tubular sylphon interposed between the steam fitting and said yoke structure responsive to the steam pressure within the fitting for maintaining the steam fitting in a balanced condition between the journal and the yoke structure.

14. In combination, a rotary conduit, a main fitting having one or more pipes attached thereto for conducting fluid to or from the interior of the fitting and serving to support the fitting, a bearing joint between the rotary conduit and the fitting, an expansible tubular sylphon compartment communicating with the interior compartment of the fitting and having a movable wall responsive to

the fluid pressure within the compartments, a yoke structure acting between the rotary conduit and said pressure responsive wall serving to carry the endwise thrust of the pressure within the fitting and tending to displace the fitting from the rotary conduit, and means exerting a pressure between said pressure responsive wall and the fitting to urge the latter toward the rotary conduit and tending to close said bearing joint, the main fitting being normally centered with relation to the rotary conduit and capable of lateral displacement from its normal position to compensate for expansion and contraction of said parts.

15. In combination, a rotary conduit, a main fitting having one or more pipes attached thereto for conducting fluid to or from the interior of the fitting and serving to support the fitting, a bearing joint between the rotary conduit and the fitting, an expansible tubular sylphon compartment communicating with the interior of the fitting and having a movable wall responsive to the fluid pressure within the compartments, a yoke structure acting between the rotary conduit and said pressure responsive wall serving to carry the endwise thrust of the pressure within the fitting and tending to displace the fitting from the rotary conduit, the fluid within the expansible compartment acting on an effective area greater than that in the main fitting, whereby to urge the latter into sealing contact with the rotary conduit, the main fitting being normally centered with relation to the rotary conduit and capable of lateral displacement from its normal position to compensate for expansion and contraction of said pipes.

16. In combination, a hollow rotary journal having an annular flange, a steam supply fitting, a bearing ring interposed between and adapted to seat against the fitting and the adjacent end of said flange, a closed compartment communicating with the interior compartment of the steam fitting and having an axially corrugated, expansible and flexible wall coaxial with the fitting and the journal, a bearing ring having radial bearing on the journal, a ring bearing against the end face of said flange at the side opposite from the fitting and having an annular steam compartment in its bearing face communicating through the radial flange with the interior of the fitting, a ring member seated on the last mentioned bearing ring and tied to the expansible end of said expansible compartment, the effective area of the expansible compartment being substantially equal to or slightly greater than the effective area within the steam fitting as well as the effective area of the compartment within the second mentioned bearing ring, and spring means operative between the fitting and the ring member tending to urge them together.

17. In combination, a hollow rotary journal having an annular flange at its end, a steam supply fitting having a concave bearing face at one end, a bearing ring having one face complementary to the bearing face of the fitting and having a straight wall bearing face adapted to seat against the end of the journal flange, a bearing ring having a radial bearing on the journal and adapted to seat against the side of the flange opposite from the first mentioned bearing ring, and means functioning between the bearing ring on the journal and the steam fitting to normally maintain the steam fitting in centered relation with the journal including a pair of diametrically disposed tie rods, each having a flexible connection with the steam fitting at its end opposite from the journal, one of the tension rods being anchored intermediate its ends to the journal so as to prevent oscillation of the fitting about the axis of the journal and the other tension rod having capacity for movement with the fitting about the axis of the first mentioned tension rod to permit the displacement of the fitting with respect to the journal due to contraction and expansion of the steam pipes.

18. In combination, a hollow rotary journal, a supporting bearing for the journal, a fitting adapted to seat against one end of the journal for delivery of fluid under pressure to or from the interior of the journal and subject to alignment displacements relative to the journal during service, a tubular sylphon mounted on the fitting at the exterior thereof and having interior communication with the fluid pressure therein, one end of the sylphon being fixed with respect to the journal bearing end of the fitting and the opposite end of the sylphon being freely responsive to said fluid pressure, a yoke structure connecting the said opposite end of the sylphon with the journal through the intermediary of a bearing ring thereon, whereby the pressure thrust tending to unseat the fitting from the journal is carried against the journal, said sylphon being of such effective area as to maintain the fitting in substantial balance, said yoke structure and said sylphon permitting said displacements of the fitting without breaking its seat against the journal.

In witness of the foregoing I affix my signature.

EARL E. BERRY.

CERTIFICATE OF CORRECTION.

Patent No. 1,896,062.

February 7, 1933.

EARL E. BEERY.

It is hereby certified that error appears in the printed specification of the above numbered patent requiring correction as follows: Page 6, line 33, claim 12, after "and" insert the word "permitting"; and that the said Letters Patent should be read with this correction therein that the same may conform to the record of the case in the Patent Office.

Signed and sealed this 28th day of March, A. D. 1933.

M. J. Moore.

Acting Commissioner of Patents.
